DESIGN FOR A COSMETIC BOTTLE

Rene Tricard, Paris, France, assignor to Lentheric
Incorporated, New York, N. Y., a corporation
of New York

Application May 12, 1933, Serial No. 48,089

Term of patent 14 years

To all whom it may concern:

Be it known that I, RENE TRICARD, a citizen of France, residing at Paris, France, have invented a new, original, and ornamental Design for a Cosmetic Bottle, of which the following is a specification, reference being had to the accompanying drawing, forming a part thereof.

In the drawing of the cosmetic bottle:
Figure 1 is a top view;
Figure 2 is a front view; and
Figure 3 is a side view.

The dominant feature of the design resides in the combination of a cylindrical body having twelve regularly spaced vertical flutings and a depressed rectangular panel midway of its height, with a comparatively large regular-dodecagonal and gently domed cap of contrasting color.

I claim:

The ornamental design for a cosmetic bottle substantially as shown and described.

RENE TRICARD.
